UNITED STATES PATENT OFFICE.

DAVID K. BILL, OF HILLSBOROUGH, OREGON.

HORSE COLLAR AND HAME.

SPECIFICATION forming part of Letters Patent No. 517,021, dated March 27, 1894.

Application filed May 12, 1893. Serial No. 473,917. (No model.)

To all whom it may concern:

Be it known that I, DAVID K. BILL, a citizen of the United States, residing at Hillsborough, in the county of Washington and State 5 of Oregon, have invented certain new and useful Improvements in Harness Collars and Hames; and I do declare the following to be a full, clear, and exact description of the invention, such as will enable others skilled in 10 the art to which it appertains to make and use the same, reference being had to the accompanying drawings, and to the letters of reference marked thereon, which form a part of this specification.

15 The special object of the invention is to make a horse-collar which shall be light, cheap and durable; flexible, cool and easy to the horse; which will not press the windpipe in going up hill, will move easily with the 20 horse's shoulders, and will cause a minimum of friction.

Figure 1 of the drawings is a side-elevation; Fig. 2 a front elevation of the invention; Fig. 3 a detail view of one of the metallic 25 stiffeners, without its covering of leather; Fig. 4 a detail view of the upper connector, and Fig. 5 a similar view of the bottom connector.

In the drawings, A A represent the two 30 sides of my combined collar and hames, B the upper connector, C the lower one, D D the stiffeners, and E E the tug-straps to which the traces are attached. Each side A is made of thick leather in one piece and smooth on 35 the inside, while the texture of the leather is soft and flexible, the requisite stiffness being given to it by the metallic reinforcement D which extends from a to a'. The ends a² a², a³ a³ are perfectly flexible and each provided 40 with a vertical slot a⁴, in which is longitudinally entered the T-head on the connectors B C which are then turned at right angles. The connectors are thus easily attached or detached, while by simply taking out one T-head from one side of the collar, at top or bottom, the collar and hames may be slipped off 45 the horse.

The stiffeners D are laid on the outside of side A and a leather strip D' sewed down 50 over them, thus inclosing them in a pocket which protects them from the weather while the side itself protects them from perspira-

tion. The short stiffeners d d are covered by the tug straps which are sewed to the sides A and a prolongation thereof—but they are 55 not absolutely necessary though preferable.

The bottom - connector is concaved to fit over the windpipe of the horse while the top one is similarly concaved to fit over a pad on the apex or ridge of the horse's neck.

The fit of this collar brings the line of draft somewhat higher on the horse's neck than the ordinary collar and enables him to pull at greater advantage, while the concave connector at the bottom effectually prevents any 65 pressure upon the windpipe. It may be used equally well for a single or double team, for heavy or light draft, and very greatly facilitates the "hitching up." One of my collars will outlast two ordinary collars, never gets 70 out of repair and never needs an extra sweat-pad. I preferably make them with half-round stiffeners of Norway or cast malleable iron and a full length tug strap without loop or buckle. The connectors may be covered 75 if desired. It will be observed that the sides A A and stiffeners D D are curved to conform to the natural shape of a horse's shoulder, while they are made of different sizes to suit large, medium or small horses.

In adjusting the collar to a horse's neck, the stiffeners are bent so as to make a snug fit and be comfortable to the horse—while the sides each move exactly with its own shoulder and hence produce scarcely any friction and no sore shoulders at all.

Having thus described all that is necessary to a full understanding of my invention, what I claim as new, and desire to protect by Letters Patent, is—

In combined collar and hames, the independent leather sections A A, having each a slot at top and bottom, the connectors B C, the stiffeners D D having each an arm, d, and the tug straps E E sewed over said arms, all 95 combined, constructed and arranged substantially as described.

In testimony whereof I affix my signature in presence of two witnesses.

DAVID K. BILL.
